(57) **CLAIM**

The ornamental design for a USB memory device, as shown and described.

DESCRIPTION

FIG. 1 is a top front right perspective view of the USB memory device.

FIG. 2 is a top plan view of the USB memory device.

FIG. 3 is a front elevational view of the USB memory device.

FIG. 4 is a right side elevational view of the USB memory device, the left being a mirror image of the right.

FIG. 5 is a bottom front left perspective view of the USB memory device where the USB connector is exposed.

FIG. 6 is a bottom plan view of the USB memory device; and, FIG. 7 is a top rear right perspective view of the USB memory device where the USB connector is exposed.
